UNITED STATES PATENT OFFICE.

GEORGE W. REEVE, OF NEVINVILLE, IOWA.

ONE-PIECE SLED-RUNNER.

1,049,601.

Specification of Letters Patent.

Patented Jan. 7, 1913.

Application filed April 4, 1912. Serial No. 688,391.

To all whom it may concern:

Be it known that I, GEORGE W. REEVE, a citizen of the United States, residing at Nevinville, in the county of Adams, State of Iowa, have invented certain new and useful Improvements in One-Piece Sled-Runners; and I do hereby declare the following to be a full, clear, and exact description of the invention, such as will enable others skilled in the art to which it appertains to make and use the same.

This invention relates to sleigh runners, and has for an object to provide a one-piece string runner which may be readily attached to a buggy box.

A further object of the invention is to provide a simple and effective means for attaching the runner to the buggy box.

With the above objects in view, the invention consists of certain novel details of construction and combination of parts hereinafter fully described and claimed, it being understood that various modifications may be made in the minor details of construction within the scope of the appended claim.

In the accompanying drawings forming part of this specification, Figure 1 is a side elevation of the runner showing the application of a buggy box thereto. Fig. 2 is a front elevation of the parts shown in Fig. 1. Fig. 3 is a detail perspective view of the hanger.

Referring now to the drawings in which like characters of reference designate similar parts, the runner is shown to be formed from a single resilient bar 33 bent to form parallel shoes 34, a rear arch 35 connecting the shoes, and a front arch 36 connecting the shoes.

Depending from the front and rear arches

of the runners are hook like hangers each consisting of a single U-shaped blank of material 37 the legs of which are bent to form hooks 38 designed to straddle the top bar of the related arch. The hooks extend below said bar and are detachably secured thereto through the instrumentality of bolts 39 passed through the extremities of the hooks and through the legs as shown. The legs of the hanger are bent abruptly near 45 the bridge portion 40 of the hanger and by this bending of the legs the said bridge is disposed in a plane at substantially a right-angle to the plane of the legs.

In applying the buggy box, the clips 41 55 which secure the elliptical springs to the axles are arranged astride of the elliptical springs and the bridge portions of the hangers, with the cross pieces 42 of the clips arranged below and bearing upon the bottom faces of the hanger bridge pieces as shown.

What is claimed, is:—

The combination with a sled runner having front and rear arches, of hangers depending from said arches each consisting of a U-shaped blank of material the legs of which are bent terminally to form attaching hooks, retaining bolts passed through said legs and through said hooks, said legs 65 being bent abruptly adjacent to said bridge portion and disposing said bridge portion in a plane at a right angle to the plane of said legs.

In testimony whereof, I affix my signature, in presence of two witnesses.

GEORGE W. REEVE.

Witnesses:

JAMES KOSAR,
